UNITED STATES PATENT OFFICE.

JOHN V. COUNTRYMAN, OF SELMA, IOWA.

SHINGLING BRACKET.

Application filed January 22, 1925. Serial 4,049.

To all whom it may concern:

Be it known that I, JOHN V. COUNTRYMAN, a citizen of the United States, residing at Selma, in the county of Van Buren and State of Iowa, have invented certain new and useful Improvements in a Shingling Bracket, of which the following is a specification.

This invention relates to improvements in shingling-brackets and has for its principal object to provide a simple and efficient means for supporting a staging or scantlings on a shingle roof so that the workmen may efficiently shingle the roof or repair the shingles already thereon.

One of the important objects of the present invention is to provide a shingling-bracket of the above mentioned character, which is of such construction as to permit the same to be readily and easily attached or detached without causing any injury to the roof or to the shingles laid thereon.

A still further object is to provide a shingling-bracket of the above mentioned character, which is simple in construction, inexpensive, strong and durable and further well adapted for the purposes for which it is designated.

Other objects and advantages of this invention will become apparent during the course of the following description.

In the accompanying drawings forming a part of this specification, and in which like numerals designate like parts throughout the following description:

Figure 1 is a side elevation of one form of the shingling bracket showing the same in use.

Figure 2 is a top plan view of the bracket.

Figure 3 is a sectional view taken approximately on line 3—3 of Figure 2.

Figure 4 is a view similar to Figure 1 illustrating another form of the shingling bracket.

Figure 5 is a top plan view of the arm associated with the shingling bracket illustrated in Figure 4 showing the manner in which the locking pin is associated therewith, and

Figure 6 is a sectional view through the locking pin and the arm.

In the drawings wherein for the purpose of illustration is shown the preferred embodiment of my invention, the numeral 1 designates an elongated arm, the same terminating at one end with the laterally ex-

tending portion 2, the end of which is curved as illustrated at 3. The purpose of this construction will hereinafter be more fully described. The opposite end of the arm or bar 1 is formed to provide the stirrup 4. The sides of the bar 1 are cut away as illustrated at 5 with reference more particularly to Figure 3 of the drawings so as to render the bar substantially T-shaped in cross section.

The laterally extending portion 2 is adapted to be disposed within an inclined opening 6 provided therefor in the roof 7 so as to cause the curved end 3 to engage the under side of the roof adjacent the opening 6 in the manner clearly illustrated in Figure 1.

A base plate 8 formed preferably of a flat strip of metal has its respective ends bent back upon themselves to provide the clip members 9, the same being adapted for detachable engagement with the stirrup 4 of the arm 1. An auxiliary plate 9' also in the form of a flat strip of metal is secured on the intermediate portion of the base plate 8 and associated therewith are the upwardly disposed standards 10 and 11, the same being arranged in spaced relation. Each of the standards includes a pair of spaced ears 12 and 13, the upper ends of which are provided with registering openings and the purpose thereof being presently apparent. Cooperating with the standards 10 and 11 are the jaw members 14 and 15 respectively, the same being provided with shank portions which are disposed between the ears of the respective standards, said shank portions being further provided with longitudinally extending slots through which extend the fastening bolts 16, the same being adapted to extend through the registering openings provided in the upper ends of the ears of each of the standards, a thumb nut 17 being associated with each of the fastening bolts 16.

Figure 5 is a top plan view of the arm associated with the shingling bracket illustrated in Figure 4 showing the manner in which the locking pin is associated therewith, and

Figure 6 is a sectional view through the locking pin and the arm.

In the drawings wherein for the purpose of illustration is shown the preferred embodiment of my invention, the numeral 1 designates an elongated arm, the same terminating at one end with the laterally ex-

tending portion 2, the end of which is curved as illustrated at 3. The purpose of this construction will hereinafter be more fully described. The opposite end of the arm or bar 1 is formed to provide the stirrup 4. The sides of the bar 1 are cut away as illustrated at 5 with reference more particularly to Figure 3 of the drawings so as to render the bar substantially T-shaped in cross section.

The laterally extending portion 2 is adapted to be disposed within an inclined opening 6 provided therefor in the roof 7 so as to cause the curved end 3 to engage the under side of the roof adjacent the opening 6 in the manner clearly illustrated in Figure 1.

A base plate 8 formed preferably of a flat strip of metal has its respective ends bent back upon themselves to provide the clip members 9, the same being adapted for detachable engagement with the stirrup 4 of the arm 1. An auxiliary plate 9' also in the form of a flat strip of metal is secured on the intermediate portion of the base plate 8 and associated therewith are the upwardly disposed standards 10 and 11, the same being arranged in spaced relation. Each of the standards includes a pair of spaced ears 12 and 13, the upper ends of which are provided with registering openings and the purpose thereof being presently apparent. Cooperating with the standards 10 and 11 are the jaw members 14 and 15 respectively, the same being provided with shank portions which are disposed between the ears of the respective standards, said shank portions being further provided with longitudinally extending slots through which extend the fastening bolts 16, the same being adapted to extend through the registering openings provided in the upper ends of the ears of each of the standards, a thumb nut 17 being associated with each of the fastening bolts 16.

Figure 5 is a top plan view of the arm associated with the shingling bracket illustrated in Figure 4 showing the manner in which the locking pin is associated therewith, and

Figure 6 is a sectional view through the locking pin and the arm.

In the drawings wherein for the purpose of illustration is shown the preferred embodiment of my invention, the numeral 1 designates an elongated arm, the same terminating at one end with the laterally ex-

will engage the upper face of the staging and securely support the same in position between the standards.

In use, the shingling-bracket is supported 5 on the roof in the manner shown in Figure 1 and will not become disengaged therefrom, thus enabling the workman to stand 10 on the staging or beam 18 and lay the shingles or repair the same without any 15 danger of falling off of the scaffold thus formed. Furthermore, provision of the inclined opening 6 will prevent the accidental displacement of the lateral extension 2 therefrom. The purpose of the cut away sides 5 20 of the arm 1 enables the lower portion of the arm to be disposed between the adjacent shingles while the bottom of the arm is adapted to rest on the shingles which are laid below the above mentioned shingles at their spaced portions. This is clearly illustrated in Figure 3 of the drawings.

In Figures 4, 5, and 6, a modification of the arm or bar is shown wherein the same comprises a bar 19, the same having a channel 20 formed in the upper face thereof and extending for substantially the full length thereof. A stirrup 21 is similar to the stirrup 4 heretofore described is formed on one end of the bar for supporting the adjacent end of the base plate 8 through the medium of one of the clips 9. A slot 22 is formed in the opposite end of the bar and one end thereof communicates with an enlarged opening 23.

35 A securing pin 24 is adapted to be removably disposed within an inclined opening 25 provided therefor in the roof 7. The pin 24 is reduced at its respective ends as illustrated at 26 and a head 27 is formed on 40 the outer end of each of the reduced portions as clearly illustrated in Figures 4 and 6. The reduced portion 26 is adapted for 45 slideable movement within the slot 22 and the head 27 will prevent the displacement of the upper end of the pin from the end of the bar 19. The head 27 is of such diameter as to be removable through the opening 23 in order to disengage the pin from the slotted end of the bar. For the purpose of 50 holding the pin 24 in locked engagement with respect to the slotted end of the bar 19, I provide the sliding locking plate 28, the same being adapted for slideable movement within the channeled portion 20 of the bar 19. A stud 29 cooperates with a longitudinal slot 30 formed in the plate 28 adjacent the outer end thereof for preventing the displacement of the locking plate from

the channeled portion of the bar. The outer end of the plate 28 is adapted to engage the reduced portion 26 of the pin 24 directly below the head 27 in the manner clearly illustrated in Figure 4 so that the pin cannot slide within the slot 22 and become disengaged from the bar. A lateral extension 31 is formed on the inner end of the locking plate 28 and provides a handle for actuating the same in its sliding movement.

With the parts arranged as shown in Figure 4 of the drawings, the pin 24 will be disposed within the inclined opening 25 provided in the roof 7 and with the locking plate 28 in locked engagement with the upper end of the pin, there will be no possibility of the bracket becoming disengaged from the roof while in use. As the staging supporting member has heretofore been more fully described, a further detailed description thereof is not thought necessary.

It will thus be seen from the foregoing description, that a shingling bracket has been provided which may be readily and easily attached or detached to the roof without causing any injury thereto or to the shingles thereon. The simplicity in which my device is constructed enables the same to be manufactured at a very low cost and will at all times be strong and durable and further save considerable time and labor in laying shingles on a roof or repairing shingles already thereon.

While I have shown the preferred embodiment of my invention, it is to be understood that various changes in the size, shape and arrangement of parts may be resorted to without departing from the spirit of the invention and the scope of the appended claim.

Having thus described the invention, what I claim is:—

A shingling bracket comprising an arm, a laterally extending member associated with one end thereof and adapted for detachable engagement with an inclined opening provided therefor in a roof, a stirrup formed on the opposite end of the arm, a base plate, a clip formed on one end thereof, said clip adapted for detachable engagement with said stirrup, a pair of standards mounted in spaced relation on said base plate between which is adapted to be received a staging, and coacting jaws secured on said standards and adapted for engagement with the outer face of the staging.

In testimony whereof I affix my signature.

JOHN V. COUNTRYMAN.
